UNITED STATES PATENT OFFICE.

CHARLES E. ACKER, OF NIAGARA FALLS, NEW YORK.

ELECTROLYTIC PROCESS OF PRODUCING NITROGEN COMPOUNDS.

No. 914,214.

Specification of Letters Patent.

Patented March 2, 1909.

Application filed October 8, 1906. Serial No. 337,976.

REISSUED

To all whom it may concern:

Be it known that I, CHARLES E. ACKER, a citizen of the United States, residing at Niagara Falls, in the county of Niagara and State of New York, have invented certain new and useful Improvements in Electrolytic Processes of Producing Nitrogen Compounds, of which the following is a specification.

This process relates to the electrolytic production of nitrogen compounds, such as nitrides, amids, cyanamids and cyanids, especially those of the alkali and alkaline-earth metals.

The process comprises the steps of electrolyzing a molten compound of the metal or base which is to be combined with nitrogen, alloying the separated metal with a cathode metal, reacting on the alloyed metal with a nitrogenous gas, and returning the residual metal to the cathode. Incidental steps are the injection of the nitrogenous gas in a direction to cause or assist the circulation of the alloy and residual metal; cooling the alloy before treatment with the gas, especially by maintaining opposed adjacent streams of the alloy and residual metal; and successively reacting on the alloyed metal and on the initial product of reaction in the presence of the residual metal.

Apparatus which may be used in carrying out the process is shown in the accompanying drawings, in which—

Figures 1, 2, 3 are vertical longitudinal sections of three different constructions, each comprising an electrolytic cell and a separate connected chamber for treating the alloy; and Fig. 4 illustrates an auxiliary gas-absorbing tower.

Each apparatus illustrated has the general construction of that heretofore devised by me for the production of caustic alkali, the electrolytic cell comprising a cast iron vessel 1 lined at the sides with magnesia brick 2, inclosed in brickwork 3 and covered by a refractory slab 4, through which pass the depending carbon anodes 5. In the bottom of the vessel is a shallow layer 6 of a molten heavy inert metal such as lead, constituting the cathode, upon which is the molten electrolyte 7. The vessel 1 is connected by delivery and return pipes or ducts 8, 9 to a separate chamber 10, into which the nitrogenous gas may be introduced by a valved pipe 11. The chamber 10 may be inclosed in the brick-work 3, as shown in Figs. 1, 3, or may be outside it as shown in Fig. 2, depending on the

temperature which it is desired to maintain therein.

The delivery pipe 8' of the apparatus shown in Fig. 1 is provided with a series of annular heat-radiating flanges 12, to cool the alloy therein. The delivery pipe 8² of the apparatus shown in Fig. 2 has a lower portion which receives a supplemental gas inlet pipe 13 and thence inclines upward to the chamber 10, the gas injected through the pipe 13 and the initial light compounds produced by the gas rising and moving along the pipe, facilitating the reaction therein. In the apparatus of Fig. 3, a portion of the delivery pipe 8³ is enlarged and receives the return pipe 9³, so that heat may be transferred from the outflowing alloy to the returning residual metal. The circulation of the alloy and metal may be effected either solely by the current of injected gas, as in the apparatus of Figs. 1, 3, or by a mechanical device, for example the screw shown in Fig. 2, or by both.

The reaction chamber 10 is of the general construction of that employed in my caustic alkali apparatus, comprising a vertical central pipe 14, which receives the molten alloy and injected gas. The nitrogen compound resulting from the reaction, being usually lighter than the residual metal, rises and collects as a floating layer, which may be run out through a suitable outlet 15, the metal returning to the electrolytic cell to reconstitute the cathode.

Specific processes which may be carried out are the production of sodium amid by the injection of ammonia into the molten sodium-lead alloy resulting from the electrolysis of a sodium compound, such as the chlorid upon a lead cathode; or the production of calcium nitrid by the injection of nitrogen into an electrolytic calcium-lead alloy. If desired, the alloy may be cooled, wholly or partially, by injecting a regulated amount of a cooled and compressed gaseous reagent, or of a volatile liquid, for example ammonia. The gaseous reagent may be diluted with an inert gas, or mixed with a hydrocarbon gas to produce carbon compounds. Solid carbon or other reagent may be introduced into the reaction chamber 10. Alkali-metal cyanids or cyanamids may be produced in this chamber by first producing sodium amid at a relatively low temperature and then reacting on the amid with carbon or a carbonaceous reagent at a

higher temperature, in the presence of the residual metal. For this purpose it is desirable to first cool the alloy, to prevent decomposition of the injected ammonia by 5 heat, or to employ the expansion of the ammonia to effect this local cooling, and to then retain the heat of reaction and supply heat by conduction from the electrolytic cell, employing apparatus of the type 10 shown in Figs. 1 and 3, in which the chamber 10 and cell are inclosed in the same brick-work. In the production of amids, some of the injected ammonia is apt to pass off without reacting on the sodium in the alloy. 15 This portion of the gas may be recovered by delivering it from the chamber 10 through a pipe 16 into the base of a tower 17, into the top of which water is sprayed through a rose 18. The gas is then recovered from 20 the aqueous solution by distillation and returned to the reaction chamber.

I claim:

1. The electrolytic process of producing nitrogen compounds, which consists in continuously electrolyzing a molten compound of a metal capable of forming nitrogen compounds, alloying the separated metal with a cathode metal, removing the alloy and reacting on it with a nitrogenous reagent, 25 separating the products of reaction, and returning the residual metal to the cathode.

2. The electrolytic process of producing nitrogen compounds, which consists in continuously electrolyzing a molten compound 35 of a metal capable of forming nitrogen compounds, alloying the separated metal with a molten cathode metal, removing the molten alloy and reacting on it with a nitrogenous gas, separating the products of reaction, and 40 returning the residual metal to the cathode.

3. The electrolytic process of producing nitrogen compounds, which consists in continuously electrolyzing a molten compound of a metal capable of forming nitrogen compounds, alloying the separated metal with a molten cathode metal, removing and cooling the molten alloy and reacting on it with a nitrogenous gas, separating the products of reaction, and returning the residual metal 45 to the cathode.

4. The electrolytic process of producing nitrogen compounds, which consists in continuously electrolyzing a molten compound of a metal capable of forming nitrogen compounds, alloying the separated metal with a molten cathode metal, removing the molten alloy and reacting on it with a nitrogenous gas, separating the products of reaction, transferring heat from another 55 portion of the molten alloy to the residual metal, and returning the heated metal to the cathode.

5. The electrolytic process of producing nitrogen compounds, which consists in continuously electrolyzing a molten compound 65

of a metal capable of forming nitrogen compounds, alloying the separated metal with a molten cathode metal, removing the molten alloy and injecting into it a compressed nitrogenous gas, thereby cooling the 70 alloy and producing a compound, separating the products of reaction, and returning the residual metal to the cathode.

6. The electrolytic process of producing nitrogen compounds, which consists in continuously electrolyzing a molten compound of a metal capable of forming nitrogen compounds, alloying the separated metal with a molten cathode metal, removing the molten alloy and injecting it into a compressed and 75 cooled nitrogenous gas, thereby cooling the alloy and producing a compound, separating the products of reaction, and returning the residual metal to the cathode.

7. The electrolytic process of producing 85 nitrogen compounds, which consists in continuously electrolyzing a molten compound of a metal capable of forming nitrogen compounds, alloying the separated metal with a molten cathode metal, removing the molten 90 alloy, converting the alloyed metal into a nitrogen compound, and returning the residual metal to the cathode, and producing the nitrogen compound by injecting a nitrogenous gas into the moving alloy. 95

8. The electrolytic process of producing nitrogen compounds, which consists in continuously electrolyzing a molten compound of a metal capable of forming nitrogen compounds, alloying the separated metal with a molten cathode metal, removing the molten 100 alloy, converting the alloyed metal into a nitrogen compound, and returning the residual metal to the cathode, and producing the nitrogen compound by injecting a nitrogenous gas into the moving alloy in a direction 105 to assist the circulation.

9. The electrolytic process of producing alkali-metal amids, which consists in continuously electrolyzing a molten compound 110 of the alkali metal, alloying the separated alkali metal with a cathode metal, removing the alloy and reacting on the alloyed alkali metal with a nitrogenous reagent, separating the resulting amid, and returning the 115 residual metal to the cathode.

10. The electrolytic process of producing alkali-metal amids, which consists in continuously electrolyzing a molten compound of the alkali metal, alloying the separated 120 alkali metal with a cathode metal, removing the alloy and reacting on the alloyed alkali metal with ammonia, separating the resulting amid, and returning the residual metal to the cathode.

11. The electrolytic process of producing alkali-metal amids, which consists in continuously electrolyzing a molten compound of the alkali metal, alloying the separated 125 alkali metal with a cathode metal, removing

- and cooling the alloy and reacting on the alloyed metal with ammonia, separating the resulting amid, and returning the residual metal to the cathode.
- 5 12. The electrolytic process of producing alkali-metal amids, which consists in continuously electrolyzing a molten compound of the alkali metal, alloying the separated alkali metal with a cathode metal, removing 10 the alloy and reacting on the alloyed alkali metal with ammonia, separating the resulting amid, returning the residual metal to the cathode, and recovering and utilizing the unabsorbed ammonia.
- 15 13. The electrolytic process which consists in continuously electrolyzing a molten compound with a molten metal cathode, removing and cooling the molten cathode product and reacting on it with a suitable agent, and 20 returning the residual molten metal to the cathode.
14. The electrolytic process which consists in continuously electrolyzing a molten compound with a molten metal cathode, removing 25 and cooling the molten cathode product and reacting on it with a suitable agent, returning the residual molten metal to the cathode, and maintaining adjacent but oppositely-directed streams of the cathode 30 product and residual metal to permit the exchange of heat between the streams.
15. A process of making alkali amid, consisting in electrolyzing a molten alkali compound in one vessel in the presence of a 35 molten metal whereby the alkali metal in the compound combines with the molten metal, passing the molten alloy into another vessel in free communication with the former and subjecting said molten alloy to the 40 action of ammonia.
16. A process of making sodium amid, consisting in electrolyzing molten sodium chlorid in one vessel in the presence of a molten metal whereby the sodium combines 45 with the metal, passing the molten alloy into another vessel in free communication with the former and subjecting said molten alloy to the action of ammonia.
17. A process of making sodium amid, 50 consisting in electrolyzing molten sodium chlorid in one vessel in the presence of molten lead whereby the sodium combines with the lead, passing the molten allow into another vessel in free communication with 55 the former and subjecting said molten alloy to the action of ammonia.
18. The process of producing alkali-metal amids, which consists in electrolyzing a molten alkali-metal compound in one vessel 60 in the presence of a molten alloying metal, passing the molten alloy into another vessel in free communication with the first vessel and cooling the alloy, and reacting on the cooled alloy with a nitrogenous reagent.
- 65 19. The process of making sodium amid, 70 which consists in electrolyzing molten sodium chlorid in one vessel in the presence of a molten alloying metal, passing the molten sodium alloy into another vessel in free communication with the first vessel and cooling the alloy, and reacting on the cooled alloy with a nitrogenous reagent.
20. The process of making sodium amid, 75 which consists in electrolyzing molten sodium chlorid in one vessel in the presence of molten lead, passing the molten sodium-lead alloy into another vessel in free communication with the first vessel and cooling the alloy, and reacting on the cooled alloy with 80 ammonia.
21. The process of producing alkali-metal amids, which consists in electrolyzing a molten alkali-metal compound in one vessel in the presence of a molten alloying metal, passing the molten alloy into another vessel 85 in free communication with the first vessel, and reacting on the alloy with a nitrogenous reagent.
22. The process of producing alkali-metal amids, which consists in electrolyzing an 90 alkali-metal compound in one vessel in the presence of a suitable liquid metal with which the freed alkali-metal will mix, passing the mixture into another vessel in free communication with the first vessel, and 95 reacting on the mixture with a nitrogenous reagent.
23. The electrolytic process of producing nitrogen compounds, which consists in electrolyzing a molten compound of a metal 100 capable of forming nitrogen compounds, alloying the separated metal with a cathode metal, removing the alloy and reacting on it with a nitrogenous reagent, separating the products of reaction, and returning the residual metal to the cathode.
24. The electrolytic process of producing alkali-metal amids, which consists in electrolyzing a molten compound of the alkali metal, alloying the separated alkali metal 110 with a cathode metal, removing the alloy and reacting on the alloyed alkali metal with a nitrogenous reagent, separating the resulting amid, and returning the residual metal to the 115 cathode.
25. The electrolytic process of producing alkali-metal amids, which consists in electrolyzing a molten compound of the alkali metal, alloying the separated alkali metal with a cathode metal, removing the alloy and reacting on the alloyed alkali metal with ammonia, separating the resulting amid, and returning the residual metal to the cathode.
26. The electrolytic process of producing 120 nitrogen compounds, which consists in electrolyzing a molten compound of a metal capable of forming nitrogen compounds, alloying the separated metal with a cathode metal, removing the molten alloy and reacting on it with a nitrogenous reagent, sepa- 125
- 130

rating the products of reaction, and returning the residual metal to the cathode.

27. The electrolytic process of producing alkali-metal amids, which consists in electrolyzing a molten compound of the alkali metal, alloying the separated alkali metal with a cathode metal, removing the alloy and reacting on the molten alloyed alkali metal with a nitrogenous reagent, separating the 10 resulting amid, and returning the residual metal to the cathode.

28. The electrolytic process of producing alkali-metal amids, which consists in electrolyzing a molten compound of the alkali 15 metal, alloying the separated alkali metal with a cathode metal, removing the alloy and reacting on the molten alloyed alkali metal with ammonia, separating the resulting amid, and returning the residual metal to the 20 cathode.

29. The electrolytic process of producing nitrogen compounds, which consists in electrolyzing a molten compound of a metal capable of forming nitrogen compounds, 25 alloying the separated metal with a cathode metal, removing the molten alloy and reacting on it with a nitrogenous reagent, sepa-

rating the products of reaction, and returning the molten residual metal to the cathode.

30. The electrolytic process of producing alkali-metal amids, which consists in electrolyzing a molten compound of the alkali metal, alloying the separated alkali metal with a cathode metal, removing the alloy and reacting on the molten alloyed alkali metal with a nitrogenous reagent, separating the resulting amid, and returning the molten residual metal to the cathode.

31. The electrolytic process of producing alkali-metal amids, which consists in electrolyzing a molten compound of the alkali metal, alloying the separated alkali metal with a cathode metal, removing the alloy and reacting on the molten alloyed alkali metal with ammonia, separating the resulting amid, and returning the molten residual metal to the cathode.

In testimony whereof, I affix my signature in presence of two witnesses.

CHARLES E. ACKER.
